FURNACE

Tom Askew Booth, London, England, assignor to
Stein & Atkinson Limited, London, England, a
company of Great Britain

Application June 6, 1940, Serial No. 339,197
In Great Britain July 5, 1939

6 Claims. (Cl. 266—33)

The invention comprises improvements in or relating to metal melting or heating furnaces and is concerned with that type of furnace (hereinafter referred to as "of the type set forth") in which heating is effected by means of internally fired tubes positioned in the lower part of the interior of the furnace where they are submerged in the metal.

It is a particular object of the invention to provide in a simple manner for the easy cleaning and/or repairing of the tubes and of the interior of a furnace of the type set forth. A further particular object of the invention is to provide a furnace of the said type which is suitable for the heating of aluminium and its alloys.

According to the present invention, a furnace of the type set forth has the heating tubes mounted in a wall of the furnace and said wall adapted for being moved away from the rest of the furnace.

In one suitable construction, the wall in which the heating tubes are mounted is adapted for being moved bodily away from the rest of the furnace to a detached position.

Several heating tubes, suitably of hairpin shape, may be mounted in an end wall through which they pass to occupy a normal position along the bottom of the furnace and the said wall may be arranged so that it can be moved away until the tubes are completely withdrawn from the interior of the furnace.

According to another construction, the wall in which the heating tubes are mounted is hinged to the rest of the furnace, for example, to the bottom part, so that it may be moved by a hinging movement away from the rest of the furnace. Such an arrangement is suitable in a small furnace having a removable lid or cover and particularly a tiltable furnace.

In opening up such a furnace the lid or cover will be first removed when the end wall carrying the heating tubes can be swung about its hinge and the heating tubes thus removed from the melting chamber of the furnace.

Advantageous embodiments of the invention will now be more fully described by way of example and with reference to the accompanying drawings wherein:

Figure 1 is a sectional elevation of a furnace in which the end wall carrying the heating tubes is movable bodily away from the other walls.

Figure 2 is a sectional plan of Figure 1.

Figure 3 is a sectional plan view illustrating the end wall of Figures 1 and 2 moved away from the furnace body.

Figure 4 is a sectional elevation of a furnace having the end wall carrying the heating tubes hinged to the furnace body, and

Figure 5 is a plan of Figure 4 but with the lid of the furnace removed.

In the particular example shown in Figures 1 to 3, the furnace is a fixed furnace of rectangular shape, but it is to be understood that the invention is also applicable to movable furnaces and to furnaces of round or other shape. In Figures 1 to 3, the walls of the furnace are lined with a layer 1 of refractory material backed with insulating brick 2 supported by a metal framework. An arched roof 3 of insulating brick is supported on the walls and, if desired, sealed against them with the aid of a sand seal as at 4. The whole of the furnace with the exception of one end wall 5 is mounted on a supporting grid of girders 6. The necessary lined openings may be variously arranged in the walls of the furnace. For example, a downwardly inclined filling spout 7 may be arranged in one side wall above a drain spout (not shown), whilst a tapping spout 8 is provided in the opposite wall and a large skimming opening 9 in the other end wall. This last opening may also be used for charging solid material into the furnace, but the filling spout 7 should be used for the introduction of molten metal.

The end wall 5 is mounted with its own lining 10 in a U-shaped metal frame 11 which embraces it along two sides and the bottom and has an inturned flange 12 extending over the edge of the inside of the wall where it normally contacts with a complementary flange 13 on a similar frame 14 at the adjacent end of the body B of the furnace. This latter frame may be provided with swing bolts 15 at the sides and bottom engageable in slotted brackets 16 on the frame 11 to permit of the end wall 5 being tightly secured to the furnace body. The end wall 5 is supported in its frame 11 upon the rear part of a four-wheeled carriage 17 capable of running on guide rails 18 extending forwardly from the end of the body of the furnace so that this end wall may be moved bodily away from the other walls of the furnace to a detached position such as is shown in Figure 3 when desired. At the top, the end wall 5 may normally engage under a projecting part of the roof as may be seen from Figure 1.

Heating tubes 19 passing through and secured in the end wall 5 normally extend along the full length of the furnace near its bottom as shown in Figure 1. The tubes are advantageously such

as are described in the specifications of British Patents Nos. 452,204, 469,114, 487,764 and 488,101 with a burner at one end and an exhausting means or eductor at the other end. Preferably, and as shown, the tubes are of hair-pin form, for instance such as are disclosed in the second of the above specifications. In this case, the hair-pin tubes may be disposed closely side-by-side and "on edge" as illustrated, the lower limbs being connected to the burners and the upper limbs to the exhausting means. A gas main 20 and an air-supply main 21 for the burners, and an exhaust hood 22, all common to all the tubes 19 are mounted above the front part of the carriage 17. These conduits 20 and 21 have readily breakable joints at 23 with fixed apparatus, a motor driven fan in the case of the air-supply main being shown at 24 in Figures 2 and 3.

Normally, the tubes extending into the furnace rest near the ends upon supports therein, such as transverse ribs 25 of refractory lining material formed on its bottom. When the end wall 5 is moved bodily away from the other walls of the furnace, the tubes 19 will also require further support. This may be provided by a cross-bar 26 temporarily placed on pedestals 27 at the sides of the rails 18 so that it lies between the partially removed end wall 5 and the end of the furnace body. The end wall may then be removed so far that the tubes are completely withdrawn from the furnace as shown in Figure 3 and both the tubes and the interior of the furnace are thus rendered readily accessible for cleaning.

In the example illustrated by Figures 4 and 5, the invention is shown applied to one form of movable furnace, in this case a tilting furnace. The tilting takes place about the axis of the shaft 28 and upon an arcuate runner 29 movable on rollers such as 30. The tilting may be effected by hand-driven worm and worm-wheel gearing 31.

In this example, one end wall 31 of the furnace is hinged to the furnace body B at 32 upon a bracket 33 secured to the frame 34 at the bottom of the adjacent end of the furnace body. The hinging may be effected by hand-operated gearing including a screwed rod 35 pivotally connected at 36 to a bracket 37 on one side of the end wall and extending through a bracket 38 fixed on the frame 34. The rod has a hand-wheel 39 applied to it on the far side of the bracket 38 and there is suitable flexibility in the parts so that, with rotating of the handwheel, the end wall 31 may be moved away from the furnace body by hinging about the axis 32 and the parts may, for instance, assume the position shown in dot and dash lines. Obviously, the lid 40 of the furnace would be removed when hinging of the end wall 31 is effected and for this purpose it may be mounted on wheels 41 movable along rails 42. The interior of the furnace and the heating tubes 43 are fully accessible when the lid 40 is removed, and the end wall 31 hinged away, from the furnace body. Some of the heating tubes in this example are shown on edge and one, the central one, is placed flatwise. Other arrangements of the tubes may be adopted, however, if desired. The end wall 31 is closed on to the body by tightening the handwheel 39 and when closed it may be secured by swing bolts 44. The tapping spout of the furnace is shown at 45, pouring by this spout being possible when the furnace is tilted. The connections of the gas and air supplies to the corresponding conduits for

the heating tubes would in this construction suitably be of flexible nature.

To ensure a good joint between the movable end wall 5 or 31 and the adjacent end of the body of the furnace, the surfaces to be brought in contact with each other may be covered with a layer of fire-clay. To facilitate breaking of this joint when the end wall is to be moved, screw-jacks may be arranged in the said wall so that they can be turned to exert pressure against the bottom and side walls of the furnace and force the end wall away.

An alternative and preferable jointing means consists in providing the flange 12 of the end wall frame 11, Figures 1 to 3, or the flange 13 of the frame 14 of the furnace body, or the similar flange 46 or 47 on Figures 4 and 5, with a depression 48 or 49 respectively extending along its length to receive a sealing material, such as sand as at 50. Preferably, and as shown, both the flanges 12 and 13, or 46 and 47 have oppositely disposed depressions 48 and 49 to form tunnels to receive the sealing material 50. The complementary depressions may conveniently form together circular channels one in each of the side walls which terminate at their lower ends in a transverse circular channel extending across the bottom of the furnace to the outer faces of the furnace walls. The sealing or packing material, such as moulding sand, is tamped tightly into the tunnels or channels.

Sometimes a difficulty is experienced with these furnaces in that, due to unequal expansions, spaces may be produced between the walls of the heating tubes and the wall of the furnace in which they are mounted so that there is a tendency for molten material in the furnace to leak through. The present invention also has for its object a construction by which the difficulties of such a leakage may be overcome and to this end a trough 51 may be provided on the outside of the end wall 5 or 31 of the furnace and this trough be filled with sealing material 52, such as moulding sand. The bottom of the trough 51 is provided with one or more doors (not shown) through which the sealing material may be removed when desired. Should it be found that there is leakage of molten material from the furnace the sealing material 52 is tamped more securely round the heating tubes.

What I claim is:

1. A metal melting or molten-metal heating furnace comprising a furnace chamber having a side opening, a closure-forming movable wall normally closing said opening, an internally-fired heating-tube apparatus mounted in said wall and constructed to normally extend inwardly therefrom along and over substantially the whole area of the lower part of the chamber interior and to be submerged in the metal within the chamber, and mounting means for said wall rendering the same movable away from adjoining walls of the furnace with the heating-tube apparatus moving therewith from its normal location within the chamber.

2. A furnace according to claim 1, wherein a trough charged with solid sealing material proof substantially against leakage of molten metal is provided on the movable wall and extended about the region thereof where the heating-tube apparatus passes through said wall so that said sealing material contacts with said heating-tube apparatus.

3. A furnace according to claim 1, wherein the heating-tube apparatus is mounted in a movable

end wall of the furnace chamber and this wall and the side and bottom walls of the furnace chamber have abutting surfaces all formed with depressions which in the closed condition of the movable wall co-operate to provide channels, said channels being filled with a solid sealing material proof substantially against leakage of molten metal.

4. A furnace according to claim 1, wherein the heating-tube apparatus is mounted in a movable end wall of the furnace chamber and the means mounting said wall is arranged so that this wall can be moved until the tube is completely withdrawn from the interior of the furnace chamber and wherein supports on which said heating-tube apparatus rests are provided in the furnace chamber and other supports on which said heating-tube apparatus temporarily rests are provided outside said chamber.

5. A furnace according to claim 1, wherein in combination with a removable lid or cover for the furnace chamber a movable end wall of said chamber having the heating-tube apparatus mounted therein is hinged horizontally to the bottom part of the furnace and means are provided for supporting and securing said movable end wall when hinged away from its closed position.

10 6. A furnace according to claim 1 having a removable lid or cover for the furnace chamber and a movable end wall hinged horizontally to the bottom of the furnace and having the heating tube apparatus mounted therein, and means for moving said end wall to its open or closed position.

TOM ASKEW BOOTH.
